Patented Aug. 17, 1965

202,015

HAIR DRYER BLOWER

Alfred W. Madl, Mequon, Wis., assignor to John Oster
Manufacturing Co., Milwaukee, Wis., a corporation of Wisconsin

Filed May 27, 1963, Ser. No. 75,073

Term of patent 14 years

(Cl. D86—10)

Fig. 4.

FIG. 1 is a front perspective view of a hair dryer blower, showing my new design;

FIG. 2 is a side elevational view on an enlarged scale thereof;

FIG. 3 is a rear elevational view thereof; and

FIG. 4 is a top plan view thereof.

I claim:

The ornamental design for a hair dryer blower, as shown.
